J. GOLDMAN

STAND LAMP

Filed Nov. 8, 1924

UNITED STATES PATENT OFFICE.

JOSEPH GOLDMAN, OF CHICAGO, ILLINOIS.

STAND LAMP.

Application filed November 8, 1924. Serial No. 748,729.

To all whom it may concern:

Be it known that I, JOSEPH GOLDMAN, a citizen of the United States, and a resident of Chicago, county of Cook, State of Illinois, have invented a new and useful Improvement in Stand Lamps, of which the following is a full, clear, and exact description.

My invention relates to improvements in stand lamps, and more particularly to that type of stand lamp which is intended to be shipped and moved about from place to place in knock-down condition, and it consists in the combinations, constructions, and arrangements herein described and claimed.

An object of my invention is to provide a stand lamp of the type described having radially extending lugs at the base which may be quickly and easily removed for the purpose of facilitating the packing and shipping of the lamp in a minimum amount of space. My improved stand lamp is particularly well adapted for shipment by express, since it can be dismantled and packed in a package which is well within the dimensional limits prescribed by the postal authorities.

A further object of my invention is to provide a device of the type described in which the leg members may be quickly and easily removed, with the utmost rigidity between the members and the members of the major portions of the stand lamp constantly maintained. Therefore there is no tendency to become infirm upon its base as frequently occurs where lamps are assembled by the provision of bolts, nuts, or the like.

A further object of my invention is to provide a stand lamp of the type described in which the construction of the leg members and the adjacent parts of the upright lamp supporting member is so constructed as to compel proper spacing of the legs of the lamp from one another, thus making it unnecessary for the person assembling the device to adjust the legs by mere guess work.

A further object of my invention is to provide a stand lamp of the type described which is simple in construction, which is durable, and which is thoroughly practical commercially.

Other objects and advantages will appear in the following specification, and the novel

features of the invention will be particularly pointed out in the appended claims. 55

My invention is illustrated in the accompanying drawings, forming part of this application, in which—

Figure 1 is a fragmentary side elevation 60 of a stand lamp embodying my invention,

Figure 2 is an enlarged view of a portion of the mechanism illustrated in Figure 1, a part thereof in section,

Figure 3 is an enlarged sectional view 65 along the line 3—3 of Figure 1,

Figure 4 is a fragmentary sectional view of a modified form of my invention, and

Figure 5 is a sectional view along the line 5—5 of Figure 4. 70

In carrying out my invention I make use of a slender upright tubular body member 1. The ordinary type of electric lamp closed socket 2 is carried at the upper end of the body member 1. Tubular ornamental sheathes 3 are disposed concentric with the body member 1 for artistic purposes. 75

A hollow leg supporting member 4, (see Figure 2) is disposed concentric with the lower end of the body member 1 and is secured thereto by the provision of exteriorly disposed threads 5 at the lower end of the body member and a threaded aperture 6 through the lower end of the member 4. The threads 5 are preferably iron pipe threads, and tapered slightly so that the member 4 may be held securely upon the body member 1 when sufficiently tightened thereon. 80

My invention relates particularly to the novel construction of the member 4, which, as Figure 3 will show, has three sets of equally spaced apart radially extending fins 6. These fins extend longitudinally on the outer tapered surface of the member 4, substantially three-fourths of the length of the member 4 starting at the upper end of the member. 85

The upper end of the member 4 is provided with a radially extending flanged portion 7 having an annular recess provided in the lowermost wall thereof as shown at 8. The fins 6 extend within the annular recess 8. 90

Three ornamental leg members 9 are provided, each of which has substantially upright portions 10 longer than the tapered surface of the member 4, which are fashioned 105

to fit, as reference to Figure 3 will show, between the adjacent fins 6. Thus the fins prevent lateral movement of the legs and serve to space the legs in their proper relation to one another. When the legs 9 are all disposed with their portions 10 contacting the tapered side walls of the member 4 between the fins 6, the foot portions of the legs lie in a common plane, and therefore provide a stable supporting means for the stand lamp. It will be noted that the upper end of the portions 10 is prevented from movement away from the member 4 by the recesses 8, which partially receive these portions.

Means for maintaining the portions 10 in the position shown in Figures 2 and 3 is provided in a locking disc 11 having a threaded aperture 12 therethrough, which is fitted upon the pipe threads 5 upon the body member 1. This locking disc 11 has an annular recess 13 concentric with the aperture 12 which is arranged to receive the lowermost ends 14 of the portion 10 of the legs 9. When the disc 11 is tightened upon the threads 5, the legs are securely held in predetermined positions relative to one another upon the leg supporting member 4.

An electric lamp cord 15 is projected through the hollow upright body member 1 and is properly connected with the electric light sockets in the cluster 2.

From the foregoing description of the various parts of the device, the operation thereof may be readily understood. When first received from the factory or shipping point, the receiver of the stand lamp will find the legs 9 disconnected from the stand lamp and the ornamental sheaths 3 properly packed in protective wrappings, and the upright body member 1 in a single piece or connected by pipe threads if the lamp is a particularly large one.

The first step in assembling the device for use is to place the sheaths 3 upon the tubular member 1. Ornamental separating discs such as shown in Figure 2 at 16, and the like are provided for lending a pleasing effect to the entire combination, and may be disposed between the adjacent ends of the sheath members 3 at the choice of the recipient, although usually a certain definite arrangement of sheaths and discs are sent out by the manufacturer. The member 4 is then disposed upon the lower end of the member 1 by tightening of that member thereupon either with the hands or a suitable wrench.

The next step in assembling the device is that of placing the legs 9 between the fins 6 and applying a disc 11 upon the lower end of the member 1 in such a manner as to draw the ends 14 of the portions 10 into close engagement with the recess 13 in the disc.

The electric light wire 15 is then con-

nected with a suitable current source and the stand lamp is ready for use.

In Figure 4 I have shown a modified form of my invention in which I employ a hexagonal surface upon the member 4 in place of the tapered surface shown in Figure 2, (see Figure 5). This construction does away with the necessity of the fins 6 since the portions 10 of the legs 9 are disposed against the alternate faces of the hexagonal surfaced member 4. Means for retaining the upper ends of the portions 10 against movement away from the member 4 is provided in a radially extending flange 17 forming a part of the adjacent sheath 3. This flange 17 has an annular recess 18 on the lower side wall thereof for receiving the upper ends 19 of the portions 10.

A disc identical in construction with the disc 11 is employed at the lowermost ends to engage the base 14 of the portions 10 in precisely the same manner as shown in Figure 2. This modified form of my invention may be cast more easily, and is particularly well adapted for use with such designs as suggest angular contour.

It is obvious that while I have here shown a leg supporting member 4 and detachable legs 9 that these same or similar members may be inverted upon a suitable upright and employed for the support of a table top or the like; thus I will have provided legs 9 for supporting an upright body member, and members similar to the legs 9 extending radially from the member 4 at the upper end of the upright member to which a table top is secured.

I deem such modifications well within the spirit and scope of my invention.

I claim:

1. A device of the type described comprising a substantially upright body member, a supporting member secured to said body member, said supporting member having a plurality of substantially vertical flat surfaces, a plurality of radial members having portions adapted to lie in engagement with the flat surface of said supporting member, a portion of said supporting member being constructed to overhang and partially receive said radial members at one end of the flattened portions, and a disc having an annular groove adjacent to the peripheral edge thereof arranged for movement on said body member, whereby said disc may be moved into engagement with the radial members at the lower parts of the flat portions thereof, these portions being received in the groove in said disc.

2. A device of the type described comprising a substantially upright body member, a supporting member secured to said body member having a plurality of substantially vertical flat surfaces, a plurality of radial members having flat portions adapted for

disposition upon said supporting member with the flat portions in engagement with the vertical surface thereof, said supporting member having a portion thereof adapted to overhang and partially receive the radial members at one end of the flattened portions, and a disc having an annular groove in one end wall thereof adjacent and concentric

with the peripheral edge thereof, said disc being mounted on said body member and adapted for movement toward the radial members, whereby portions of said radial members adjacent the lower end of the flattened surfaces thereof may be received within said annular groove. 10

JOSEPH GOLDMAN.
